UNITED STATES PATENT OFFICE.

MYRON H. KINSLEY, OF NIAGARA FALLS, NEW YORK.

DESIGN FOR A SPOON OR FORK HANDLE.

SPECIFICATION forming part of Design No. 14,608, dated February 5, 1884.

Application filed November 26, 1883. Term of patent 7 years.

To all whom it may concern:

Be it known that I, MYRON H. KINSLEY, of Niagara Falls, in the county of Niagara and State of New York, have invented a new Design for Spoon and Fork Handles; and I do hereby declare the following, when taken in connection with accompanying drawing and the letters of reference marked thereon, to be a full, clear, and exact description of the same, 5 and which said drawing constitutes part of this specification, and represents a face view.

This invention relates to a design for the handles of spoons, forks, and like articles of table-service; and it consists in the configuration and ornamentation of the handle, as hereinafter described, and shown in the accompanying illustration.

The handle gradually expands from near the bowl to the end. At the end the handle is cut 20 square across and the angles cut away in concave shape. From the boss *a* a bead at the edge follows the line of the sides of the handle and the curves at the angles, but across the top, is curved in concave shape—that is, 25 curved downward onto the face of the handle. At the extreme tip the space above the concave portion of the bead is filled by a fan-shaped ornament. Springing from the center

across the face is a plain band, *b*, bordered by a bead at the top and bottom. On the space 30 below is a diagonal plain band, *c*. Across the face, between the plain band *b* and the point where the diagonal band *c* starts, is a transverse ornamental band, *d*. The surface within the bead, except the plain bands *b* and *c*, is 35 matted and ornamented by tracery, as shown in the accompanying illustration. This ornamentation may be varied without materially changing the design.

I claim—

The herein-described design for spoon and fork handle, consisting in the handle gradually expanding to the end, the tip square, the angles cut concave, the edges beaded, the bead following the line of the edges to the tip, and 40 there curved down onto the face of the handle, a plain band, *b*, transversely across the face of the handle between the beads, and a diagonal plain band, *c*, below, the remaining space within the handle ornamented, substantially as described, and shown in the accompanying illustration.

MYRON H. KINSLEY.
